UNITED STATES PATENT OFFICE.

FRED B. IDE, OF TROY, NEW YORK, ASSIGNOR TO ETTIE M. IDE, OF SAME PLACE, WILLIAM GRIFFIN, OF WEST TROY, AND NATHAN D. IDE, OF CORINTH, NEW YORK.

RAILWAY TIME-SIGNAL.

SPECIFICATION forming part of Letters Patent No. 449,584, dated March 31, 1891.

Application filed December 26, 1890. Serial No. 375,855. (No model.)

To all whom it may concern:

Be it known that I, FRED B. IDE, of the city of Troy, county of Rensselaer, and State of New York, have invented a new and useful 5 Improvement in a Mechanism for Automatically Indicating the Time at which Railroad-Trains Pass Stations, of which the following is a specification.

My invention relates to a mechanism for 10 automatically indicating in connection with a clock designating the time of day or night and indicators operated by the clock independently of its ordinary hands to designate in minutes upon a graduated scale the time 15 at which trains pass the station at which the apparatus is located, the object and purpose of my invention being to indicate to following trains the time at which a next preceding train had passed, so that succeeding trains may 20 avoid running too close to preceding trains, and thus avoid the dangers of collision.

My invention consists (as will be more fully detailed hereinafter in connection with its 25 illustration) in the combination, with a clock constructed and operated to indicate passing time in the ordinary manner, of a mechanism operated by a passing train to connect with said clock and to be actuated by the latter to indicate in minutes by means of indicators 30 and figures the interim between the time of the passage of a train and a succeeding period covering a part of an hour.

My invention also consists (as will be more fully detailed hereinafter in connection with its 35 illustration) in the sub-combination of the parts where they perform specific function.

Accompanying this specification to form a part of it there are four plates of drawings containing eleven figures illustrating my invention, with the same designation of parts 40 by letter-reference used in all of them.

Of the illustrations, Figure 1 is a front elevation of the clock and the case or inclosure in which the clock and mechanism connecting therewith are placed, showing also the time-figures and pointer arranged on the case, with the track and the support on which the case 45 rests shown in cross-section. Fig. 2 shows a side view of the apparatus illustrated at

Fig. 1, with that side of the case that is next 50 adjacent to the track facing the view and with the supplemental wheel upon a passing car-truck in engagement with the mechanism operating the connection made with the clock and pointer. Fig. 3 is a section taken on the 55 line $x' x'$ of Fig. 2, with the timing mechanism and pointer shown as connected with the clock and in shape to indicate the time at which the train which made the timing connection had passed. Fig. 4 is another section 60 of the same parts, taken on the line $x' x'$ of Fig. 2, with the timing mechanism being operated by the clock and with the pointer in the position shown in Fig. 1, showing that the last train had passed the station fifteen minutes before. Fig. 5 is a cross-section taken on the line $x^3 x^3$ of Fig. 4. Fig. 6 is an enlarged elevation of the clock and connected timing mechanism, with its rear face fronting the view. Fig. 7 is a section taken on the line $x^4 x^4$ of Fig. 6. 70 Fig. 8 is a central vertical section of the cylinder and piston, which latter as actuated by a passing car-truck operates the connection made between the timing mechanism and the clock, with the parts in this figure shown in a 75 larger scale than in the other figures. Fig. 9 is a perspective of a latch-slide. Fig. 10 is a section taken vertically and centrally through the latch-slide and latch; and Fig. 11 is a view of the end of the lift-bar which connects with 80 the piston-rod to raise the latch.

The several parts of the apparatus thus 85 illustrated are designated by letter-reference and the function of the parts is described as follows:

The letter T designates the rails of the track; C', the clock case or inclosure arranged upon a support S, running across the track beneath the rails. This case or inclosure C' is arranged at one side of the track, so that the dial d of 90 the clock C^2 will face at right angles to the track.

The letter N designates a pit or trough made beneath the rails and at right angles to the track, the support S, before named, forming the top of the pit.

The letter A designates a spring-plate, which has a top p' and vertical sides p^2 ,

which are each notched out centrally at p^3 , and which when at rest rise from the ends to the center, as shown by the dotted line p^4 of Fig. 2.

- 5 The letter B designates a bar that is arranged between the sides p^3 of the spring-plate A, and down over the sides of which bar the sides of said spring-plate slide when the spring-bar is forced down by a passing car.
10 This bar and the spring-plate A are shown at Figs. 2 and 4.

The letter P designates a piston-rod, the upper end of which passes through the bar B and is there secured to the top of the spring-plate A.

The letter C⁵ designates a cylinder in which the piston P² is operated, as will be more fully described hereinafter.

The letter a designates an arm that is rigidly connected to the piston-rod P at right angles thereto, and at its outer end at a³ is extended downwardly, and then laterally at a³, which lateral extension or lift-bar at its outer end is constructed with a latch-catch a⁴.

25 The letter L designates a latch-slide, which is shown in perspective at Fig. 9 and in vertical section at Fig. 10. This latch-slide is attached at l² to the side of the pit N.

The letter L² designates a latch that is provided with a latch-notch l³ and an offset hook l⁴, projected through a slot l⁵, made in the side of the latch-slide L, there being a stop l⁶ made in this slot, with which the hook l⁴ engages when down to regulate the distance at which 35 the latch shall descend.

The letter n designates a pulley having a pintle-shaft n² secured to the side wall of the pit, and b a chain, one end of which connects with the hook l⁴ on the latch, with the other 40 end of the chain connecting with the end e of the lever E, which at e³ is pivoted to the side of the pit N.

The letter W designates a counterpoise arranged upon an arm e³ of the lever E.

45 The letter E² designates a connecting-rod which passes upwardly through the slot e⁵ made in the support S, the lower end of which connecting-rod is pivotally connected at e⁷ to the pivoted lever E, and its upper end at e⁶ is 50 pivoted to the rack-bar B², arranged to be moved in guides g' g² within the case C'.

The letter R' designates a rack made at the upper end and upon the side of said rack-bar within a groove g³ made in the latter, and the 55 letter R² designates another rack made in the side edge of said rack-bar, which last-named rack is made in said bar below the rack R'.

The letter I designates a pinion having a pintle-shaft i² secured to the wall of the case 60 C', which pinion is adapted to mesh into the rack R² on the rack-bar B².

The letter k designates a geared segment that is arranged to mesh into said pinion I, and this segment is provided with a shaft b⁶, 65 to which it is keyed, so as to turn with it, and which shaft has its bearing in the wall of the case, and where projected through the latter

is connected to a pointer J, so that as said rack-bar is moved up or down said pointer is also moved to turn back and forth.

The letter m designates a gear-wheel arranged to turn on the shaft m², and the letter w² a gear-wheel arranged to turn on said shaft m², back of the gear-wheel m, as shown by the dotted line d² of Fig. 6.

The letter m³ designates a spring-pawl that is arranged on the back of the wheel m, and r⁴ a ratchet arranged on the front face of the wheel w², so that said wheel m may be rotated in one direction without turning the wheel w².

The letter h designates a pinion having a pintle-shaft h² fixed in the frame F, and this pinion meshes into the gear-wheel w² and also into the gear-wheel w³, the latter being arranged on so as to turn with the minute-hand 85 shaft h⁴ of the clock C². The wheels w² and w³ are to be of the same size and have the same number of teeth, so that when actuated by the pinion h they turn with the same speed, and the wheel m, by means of its ratchet-and-pawl 90 connection with the wheel w², turns with the same speed as the latter. This wheel w³ on the minute-hand shaft of the clock makes one revolution an hour and actuates the wheels w² and m to make the same time. The wheel m 95 has the same number of teeth as the wheels w² and w³.

As thus made and arranged, the rack-bar B², when moved up to the full extent of its traverse, moves the wheel m on its shaft 100 without turning the wheel w², and as the rack R' engages with the wheel m, and rack R², actuated by the latter, meshes into the pinion I, engaging with the segment k, the latter moves the pointer J, so that it will be opposite O of the dial D. This dial is divided 105 off into four spaces of five minutes each, and with the mechanism thus connected with the clock, as the minute-hand shaft revolves at each minute, it actuates the wheel m to move 110 one tooth, and the rack R², by means of its connection with the pinion I, operates the segment k, so that the pointer J will move one minute on the dial D.

To use the apparatus in the night-time and have it designate the time at which the last train had passed, there is arranged in the case or inclosure C', in its front face, a glass pane Q, upon which there is a column of figures (indicated at Q²) denoting minutes, which increase 115 from five to twenty by an addition of fives. Back of the pane of glass there is a slide-plate d⁵, arranged to move in guides G³ G⁴, made in the sides of the inclosure C', as shown at Fig. 5, said slide-plate being arranged adjacently 120 to the pane Q. This slide-plate is made to have a central pane of red glass y, which is large enough, when opposite either of the figures in column Q², to show (from the effect of a light placed behind it upon the bracket b⁸) 125 the number at which the small pane is opposite in a red or danger field. This slide-plate d⁵ is attached to an arm a⁶, that is connected to the rack-bar B² and projected laterally 130

therefrom at right angles thereto by means of a ring r^6 on the frame encircling said bar and a set-screw t^6 , as shown at Figs. 3 and 4, so as to be moved up or down with the rack-bar as the latter is operated to move upwardly to connect with the clock or moved downwardly by the latter, as before described. As this slide-plate is thus moved down it brings the red field opposite the numbers in the column Q^2 in their order. Thus when the figure "5" appears in a red field it indicates that a train had passed the station five minutes before the observation was made.

The piston-rod P connects with the piston P^2 , which latter has an inverted-**U** form and made with an interior chamber v^2 . This piston is provided with packing p^6 , so as to make an air-tight engagement with the inner face of the cylinder C^5 .

20 The letter t designates a tube connecting with the chamber v^2 , formed in the piston-head, and this tube extends downwardly through the cylinder-head h^4 through an opening h^5 .

25 The letter S^4 designates a spiral spring encircling the tube t between the piston P^2 and the cylinder-head h^4 , as shown at Fig. 8.

The letter V designates a valve arranged in the chamber v^2 , so as to open or close the upper end of the tube t . This valve V opens when the piston is forced downwardly within the cylinder and closes when the piston rises, so that air may enter when the valve is open and be prevented from entering when the piston rises.

30 The letter O^2 designates a passage made in the piston-head leading from the chamber v^2 into the cylinder interior i^4 , and O^3 is a passage-way leading from the latter through the top head of the cylinder C^5 into the outer air.

40 The letter s^6 designates a spiral spring arranged between the valve V and the top of the chamber v^2 , and the function of this spring is to insure the prompt closing of the valve V when the piston rises.

45 As thus made and arranged, when the piston P^2 is forced down within the cylinder C^5 it is so moved against an air-cushion within the latter and against the force of the spring S^4 , the air slowly escaping through an opening O^4 , leading from the cylinder C^5 into the tube t , with air entering through the tube t into the chamber v^2 , and from thence passing into the cylinder interior i^4 above the piston through the opening O^2 . When the piston rises, then the valve V closes and the air within the cylinder above the piston slowly escapes through the opening O^3 . This operation of the piston secures an elastic movement without jar or concussion.

50 The letter M designates a wheel arranged upon an outrigger-shaft f^2 , projected laterally beyond the track from the truck of a car, so that when the car is moving along upon the rails to pass the station at which the apparatus is placed this wheel M will engage with the spring-plate A , so as to force down the

latter and the piston-rod P , connected with the plate, with the parts in position, as shown at Fig. 2. When the piston-rod and piston are thus forced down, the laterally-projected arm a is also forced down, as well as the latch-catch a^4 thereon and within the latch-slide L , so that said latch-catch hooks onto the notch l^3 of the latch L^2 . When the piston after being thus forced down rises, the engagement of the latch-catch with the latch raises the latter within the latch-slide, as shown at Fig. 3, until the bevel b^7 on the catch a^4 meets with the bevel b^7 at the end of the latch-slide, when the latch slides from off the catch and descends to the position shown at Fig. 4. When the latch is being thus raised by means of its engagement made with the chain and the offset hook l^4 , it pulls upwardly on the chain b and carries the latter where it passes over the pulley n to pull down on the lever E to raise the rod E^2 and the rack-bar B^2 to connect the latter with the pinion I and to connect the upper rack on the rack-bar B^2 with the clock, as before described.

The counterpoise W is constructed to have the apparatus balance on the pivotal connection e^2 of the lever E , so that there will be but little, if any, strain upon the clock capacity to move down the rack-bar B^2 .

55 While I have shown the dial D as operated to indicate by division an interval of twenty minutes, the dial may, as to its time indication, be increased or diminished, as may be desired, by increasing or diminishing the length of the rack upon the rack-bar and the arc of the segment and increasing or diminishing the distance of the rack-bar movement. When the racks engage with the clock, this engagement continues until the rack-bar is moved down, so as to cease engaging with the clock mechanism.

60 Any kind of clock may be used in which there is a minute-hand shaft that is actuated to make one revolution in an hour, and upon which a gear-wheel may be attached to move with the same speed, and by which the rack-bar may be operated, as I illustrate and describe.

65 As thus constructed and arranged a series of such mechanisms and apparatus may be placed at the side of a railway-track, and the engineer of a passing train by looking at it day or night can tell the time at which a preceding train had passed if such passage was made within the limit expressed upon the apparatus by the figures thereon.

70 As the connection made by the rack-bar with the clock performs a specific function in operating the geared segment and pointer, as well as the sliding plate having the red-glass panel therein, I do not limit my invention to these factors, as I arrange and construct them to be operated to connect by a passing car-truck to the particular means which the latter moves to make such connection.

75 Having thus described my invention, what

I claim, and desire to secure by Letters Patent, is—

1. In an apparatus for automatically indicating the time at which railway-trains pass stations, the combination, with a clock indicating time in the ordinary manner and arranged upon the side of the track, of a minute-dial arranged upon the case of said clock below the latter, a pointer for said dial, and a rack-bar constructed with a rack operated to connect with said clock mechanism by the truck of a passing car, with said rack-bar operated by said clock to communicate motion to said pointer to indicate minutes upon said minute-dial, substantially as shown and described.

2. The combination, with a clock located at the side of a railway-track, of a rack-bar provided with a rack operated to rise and engage with the mechanism of said clock by a passing rail-truck and operated to descend by the engagement of said rack with the clock mechanism, substantially as described, a translucent panel having minute-designating figures thereon and arranged in the front face of the clock and rack-rod inclosure, and a slide-plate having a red-glass panel behind said translucent panel, said slide-plate being connected to said rack-rod to be moved downwardly by said clock mechanism, substantially as herein shown and described.

3. The combination, with a clock located at the side of a railway-track, said clock having upon it a gear-wheel adapted to be moved by its minute-hand shaft one tooth a minute and to be reversed without engagement with the clock mechanism, substantially as described, of a rack-bar having a rack at its upper end and constructed to be moved upwardly to engage with said gear-wheel by a passing car-truck and operated to be moved downwardly by the connection made with said gear-wheel and its connection with said clock mechanism, a second rack arranged upon said rack-bar below the before-named rack, said second rack being constructed to engage with a pinion arranged on the clock case or inclosure interior, a dial indicating minutes arranged on the front of said clock-case below the clock, and a pointer having a segmental gear on its shaft adapted to mesh into said pinion and be operated thereby to indicate minutes on said dial, substantially as shown, and for the purposes set forth.

4. The combination, with the gear-wheel w^3 , arranged upon and constructed to be moved by the minute-hand shaft t^4 of the clock C^5 ,

substantially as described, of the pinion h , having a shaft h^2 in the clock-frame, the gear-wheel w^2 , made with a ratchet-wheel r^4 and arranged on the shaft m^2 and adapted to mesh into said pinion, the wheel m , made with a spring-pawl m^3 and arranged on said shaft m^2 in front of the wheel w^2 , the rack-bar B^2 , made with the edge groove g^3 , and interiorly-placed rack R , constructed and arranged to be operated substantially in the manner as and for the purposes set forth.

5. The combination, with the cylinder C^5 , arranged at the side of a railway-track, made with the vent-passage O^3 , of the piston P^2 , having the piston-rod P , interior chamber v^2 , vent-passage O^2 , valve V , the tube t , having an air-passage O^1 , the spring S^4 , arranged between said piston and the cylinder-head h^4 , the spring-plate A , connected to the top of the piston-rod, and the wheel M , arranged on an outrigger-shaft projected laterally from a car-truck, substantially in the manner as and for the purposes set forth.

6. The combination, with the cylinder C^5 , of the piston P^2 , having a piston-rod P , made with an arm a and constructed to be moved elastically within said cylinder, substantially as described, the spring-plate A , connected to said piston-rod and adapted to be operated by a passing car-truck, substantially as described, the latch L^2 , the rack-bar B^2 , connecting-rod E^3 , lever E , made with a counterpoise, and the chain b , connecting the lever E with the latter, substantially as and for the purposes set forth.

7. The combination of a cylinder having a piston that is provided with an arm and constructed to be operated to elastically descend and rise within said cylinder by the truck of a passing railway-car, a slide-latch operated by said piston, a clock located at the side of the railway-track, a rack-bar operated to rise and connect within said clock and operated to descend and actuate a timing mechanism by said clock, a pivoted lever provided with a counterpoise connected at one of its ends by means of a rod with said rack-bar, and the other end of said lever connected by a chain with said latch, substantially in the manner as and for the purposes set forth.

Signed at Troy, New York, this 22d day of December, 1890, and in the presence of the two witnesses whose names are hereto written.

FRED B. IDE.
